UNITED STATES PATENT OFFICE

2,439,013

APPARATUS FOR THE CONTROL OF
HIGHWAY CROSSING SIGNALS

Carl F. Lower, Edgewood, Pa., assignor to The Union Switch & Signal Company, Swissvale, Pa., a corporation of Pennsylvania

Original application December 15, 1944, Serial No. 568,288, now Patent No. 2,406,955, dated September 3, 1946. Divided and this application March 12, 1946, Serial No. 653,728

3 Claims. (Cl. 246—130)

1

My invention relates to apparatus for the control of highway crossing signals, and more particularly to apparatus for controlling operation of the highway crossing signal in accordance with the speed of the train.

The present application is a division of my co-pending application Serial No. 568,288, filed December 15, 1944, for Apparatus for the control of highway crossing signals, now Patent No. 2,406,955, dated September 3, 1946.

A highway crossing signal is frequently controlled through a time measuring means which is governed by the track circuit of an approach time measuring section. The control of the signal is such that operation of the signal is delayed when the time measuring means has been operated for its predetermined interval indicating the train speed to be less than the preselected value.

Accordingly, a feature of my invention is the provision of novel and improved apparatus for control of highway crossing signals according to the speed of the train.

An additional feature of my invention is the provision of novel and improved apparatus controlled by a train as it travels through two or more consecutive track sections in the approach of a highway crossing to initiate the operation of a highway crossing signal when the train exceeds the limit of speed preselected for each section.

Other features, objects and advantages of my invention will appear as the specification progresses.

The above features, objects and advantages of my invention are obtained by forming the track on the approach side of a highway crossing into a series of consecutive sections, each of which is provided with a track circuit. The number of such sections is predetermined according to the maximum permissible speed for all trains, and according to the permissible variations in the warning period of the signal. The section most remote from the intersection is used as a time measuring section, sections nearer to the intersection are used both as a time measuring section and as an operating section, and the section adjacent the intersection is made a positive operating section.

A separate time measuring means is preferably associated with each time measuring section, and each such means is adjusted for an operation period which is preselected to agree with the time consumed by the train in traveling the associated section at a predetermined speed. Each of

2

the time measuring means is effectively energized for operation thereof through a circuit including a back contact of the track relay of the associated section so that each time measuring means is operated while a train is moving through that section. If a time measuring means completes its movement indicating that a train is traveling at a speed below the speed limit prescribed for the respective section, the warning operation of the signal is held in abeyance while the train occupies the section next toward the intersection. In this way the point at which the warning operation of the signal is started is dependent upon the speed of the train.

I shall describe one form of apparatus embodying my invention, and shall then point out the novel features thereof in claims.

The accompanying drawing is a diagrammatic view showing one form of apparatus embodying my invention.

Referring to the drawing, the reference characters 1a and 1b designate the track rails of a stretch of track over which traffic normally moves in the direction indicated by an arrow and which track is intersected by a highway H. The rails on the approach side of the highway are formed by the usual insulated rail joints with a series of consecutive track sections 1T, 2T, 3T and 4T, and which track sections a train traverses in the order reverse to that named as it approaches the highway. Each of these track sections is provided with a track circuit including a source of current such as, for example, a battery TB connected across the rails at one end of the section and a track relay designated TR plus a numeral or letter corresponding to that of the section connected across the rails at the other end of the section. These track sections are made of predetermined lengths which are made to agree with the maximum permissible speed for all trains and with the warning period of the highway crossing signal.

To aid in the understanding of the invention, I shall assume that the maximum permissible speed for all trains is 90 miles per hour and that a minimum warning period of twenty seconds prior to the arrival of a train at the intersection for the highway crossing signal is required. Under such circumstances, the section 1T may be 880 feet in length and forms a 0 to 30 miles per hour zone because a train operating at 30 miles per hour travels 880 feet in 20 seconds. For train speeds less than 30 miles per hour the warning period of the signal would be correspondingly higher. Section 2T may also be 880 feet in

length and the two sections 1T and 2T may be considered as a 30 to 60 miles per hour zone. That is, the combined length of the sections 1T and 2T is 1760 feet to provide 20 seconds warning period of the signal for a train traveling at 60 miles per hour. For trains traveling at a speed between 30 and 60 miles per hour, the warning period of the highway crossing signal would be correspondingly increased but would not exceed 40 seconds. Likewise, the section 3T may be 880 feet in length and the three sections 1T, 2T and 3T serve as a 60 to 90 miles per hour zone, because the combined length of the three sections is 2640 feet and they provide 20 seconds warning period for a train moving 90 miles per hour. Section 4T is a measuring section and it may be of any suitable length and by way of illustration I shall assume it is 880 feet in length. As will appear hereinafter, the section 1T is a positive operating section, and the operation of the signal is effected when a train occupies this section whether the train is moving or not. Section 2T is an operating section, and section 3T is a section used both as a measuring section and as an operating section. Section 4T as stated above is a measuring section.

It is to be understood, of course, that my invention is not limited to this one arrangement of track sections and a larger or a smaller number of sections may be used and the sections may be of different lengths, the length of the sections being made to suit the train speeds and the warning period of the signal at the particular location.

A highway crossing signal S is located at the intersection, and this signal may be any one or a combination of the several types of such signals, and as here shown it is an audible signal in the form of an electric bell. The immediate control of the signal S is effected through a signal control relay EXR, the arrangement being such that when relay EXR is energized the bell S is silent, but that when the relay EXR is deenergized and released to close back contact 10 an obvious circuit is completed and the bell is energized to sound a warning.

Control relay EXR is governed through a line circuit having three alternative paths. The first one of these paths is that by which the relay is normally energized and extends from terminal B of a convenient source of current, such as a battery not shown, through front contact 11 of track relay 3TR, front contact 12 of track relay 2TR, checking contact 13 of a relay 1ETR, to be referred to shortly, front contact 14 of track relay 1TR, checking contact 15 of a relay 2ETR, also to be referred to shortly, and winding of relay EXR to terminal C of the source of current. A second path includes terminal B, front contact 16 of track relay 2TR, front contact 17 of relay 1ETR, wire 18, front contact 14 of relay 1TR and as previously traced for the first path. A third path includes terminal B, front contact 19 of relay 1TR, front contact 20 of relay 2ETR, wire 21 and winding of relay EXR to terminal C. It follows that when sections 1T, 2T and 3T are unoccupied and each of the relays 1ETR and 2ETR is set at an initial position, the control relay EXR is energized. Also, when section 3T is occupied to shunt track relay 3TR and the sections 2T and 1T are not occupied, relay EXR is energized providing the relay 1ETR is operated to close the contact 17 and complete the second branch path of the control circuit. Again, when section 2T is occupied to shunt track relay 2TR, the control

relay EXR is energized through the third path of the control circuit providing the relay 2ETR is operated to close contact 20. If section 1T is occupied to shunt track relay 1TR relay EXR is de-energized.

Relays 1ETR and 2ETR are time element relays. They are preferably alike in construction and may be any one of several types. Their construction may be, for example, similar to that disclosed in Letters Patent of the United States No. 1,966,965, granted July 17, 1934, to Branko Lazich and Harry E. Ashworth, for Electric relays, except as the structure is modified to respond to recurrent or time spaced impulses. It is sufficient for this application to point out that relay 1ETR, for example, is provided with a clutch or holding winding 22, an operating winding 23 and a ratchet operated armature having three circuit controller contact members 24, 25 and 26 attached thereto. The arrangement is such that when clutch winding 22 is deenergized, the armature falls by its own weight or by a bias to an initial position, that is, to the position where the contact members 24, 25 and 26 occupy the positions illustrated in the drawing. In this initial position, the contact member 25 engages contact 13 to check the initial position of the armature. When clutch winding 22 is energized, and the operating winding 23 is supplied with time spaced impulses, the armature is operated in a step by step movement away from the initial position to an extreme or operated position. In this movement contact member 25 disengages contact 13 immediately after the armature leaves the initial position and the contact members 24 and 26 engage contacts 17 and 27, respectively, only at the extreme position. The number of impulses required to complete such a movement is predetermined by an adjustment of the relay. Thus with impulses of a pre-selected frequency or code rate, the operating time of the relay can be preselected. For example, if the impulses are of a rate of 75 impulses per minute and the relay is adjusted to require 8 impulses to complete its movement, the contact members 24 and 26 engage their respective contacts 17 and 27 in 10 seconds, this being the operating time indicated in the drawing. The connection for the operating winding 23 is opened at the extreme position to discontinue further movement of the armature and if the clutch or holding winding 22 remains energized the armature is retained at this extreme position. It is to be noted that energization of the operating winding 23 without energization of the clutch winding 22 is ineffective to operate the relay. Also, the armature is restored immediately to the initial position from any intermediate position in the event the clutch winding 22 becomes deenergized.

The time element relay 2ETR is similar to relay 1ETR but it is adjusted to operate its contact members 28 and 29 to close contacts 20 and 30, respectively, in response to 16 impulses of a 75 code rate, that is, it closes the contacts in 20 seconds. Contact member 31 of the relay 2ETR engages contact 15 to check the initial position of the relay.

Code impulses are supplied to the operating windings 23 and 34 of the two time element relays through a continuously operating code transmitter CT which is operated to close its contact 32 at the code rate of 75 times per minute. The circuit through which such code impulses are supplied extends from terminal B of the source of current through contact 32 of coder CT, wire

33, and the two operating windings 23 and 34 in multiple to terminal C of the current source.

The clutch winding 22 of relay 1ETR is controlled by a line circuit having two alternative paths. A first circuit path extends from terminal B through back contact 35 of track relay 4TR of the time measuring section 4T, front contact 37 of track relay 3TR and winding 22 of relay 1ETR to terminal C. The second path includes terminal B, front contact 27 of relay 1ETR, front contact 38 of track relay 2TR and winding 22 to terminal C. It is to be seen, therefore, that when a train occupies the measuring section 4T to shunt relay 4TR closing back contact 35, and section 3T is unoccupied so that track relay 3TR is picked up closing front contact 37, the time element relay 1ETR is operated from its initial position toward its extreme position. If a train moves through the section 4T at a speed above 60 miles per hour and consumes less than 10 seconds in passing through the section and entering section 3T to shunt track relay 3TR, the time element relay 1ETR is deenergized causing its armature to fall back from whatever position it had been advanced to the initial position. If the train is moving at less than 60 miles per hour and consumes more than 10 seconds in moving through the section 4T so that the contact member 23 engages contact 27 to complete the second path for winding 22, the relay is retained energized at its extreme position after the train enters the section 3T and remains at its extreme position until the train enters the section 2T and shunts the track relay 2TR.

Similarly, the clutch winding 42 of time element relay 2ETR is controlled through a line circuit having two branch paths, a first one of which extends from terminal B through back contact 40 of track relay 3TR, front contact 41 of track relay 2TR and clutch winding 42 to terminal C; and a second one of which paths includes terminal B, contact 30 of relay 2ETR, front contact 43 of track relay 1TR, winding 42 and terminal C. It follows that when a train occupies section 3T to shunt track relay 3TR closing back contact 40, the time element relay 2ETR is operated from its initial position toward its extreme position. If the train is traveling at less than 30 miles per hour so that it consumes something over 20 seconds in moving through section 3T, the time element relay 2ETR is operated to its extreme position closing contact 30 and the relay is retained energized at its extreme position while the train travels the section 2T. If the train is moving through section 3T at a speed above 30 miles per hour and consumes less than 20 seconds, then the time element relay 2ETR is reset to its initial position when the train enters the section 2T. The two time element relays 1ETR and 2ETR control alternative paths in the line circuit for the control relay EXR in the manner explained hereinbefore.

Assuming the apparatus to be normal, that is in the position illustrated in the drawing, and a train moving at 90 miles per hour approaches the intersection, the time element relay 1ETR is operated while this train moves through the measuring section 4T, but since the train consumes only a little over 6 seconds in moving through section 4T, the relay 1ETR does not complete its movement and is deenergized and restored to its initial position when the train enters the section 3T. When the train shunts the track relay 3TR to close back contact 40, the second time element relay 2ETR is operated but since

this train will consume only about 6 seconds in moving through the track section 3T, the relay 2ETR is deenergized and restored to its initial position when the train enters the section 2T to shunt track relay 2TR.

When the track relay 3TR was released to open front contact 11 in response to the train entering section 3T, the control relay EXR is deenergized and initiates the warning operation of the highway crossing signal S because neither one of the two alternative paths for the relay EXR is closed by the time element relays. Consequently, for this train traveling at 90 miles per hour, the signal S is operated while the train is moving through the three sections 3T, 2T and 1T and a 20 seconds warning period is effected.

Assuming a train traveling at a speed just under 60 miles per hour approaches the intersection, the train consumes slightly over 10 seconds in traveling the measuring section 4T and the first time element relay 1ETR completes its operation and is retained at its extreme position through the branch path including its own contact 26 when the train enters the section 3T. With relay 1ETR held at its extreme position, the control relay EXR is retained energized by the branch path through contact 17 of relay 1ETR, while the train occupies the section 3T. The second time element relay 2ETR is set into operation when the train enters section 3T to shunt track relay 3TR and close back contact 40. This train will consume only a little over 10 seconds in advancing through section 3T, and relay 2ETR whose operating period is 20 seconds is deenergized and restored to its initial position when the train enters section 2T to shunt relay 2TR. The release of relay 2TR opening front contact 27 causes relay 1ETR to be deenergized and restored to its initial position and in turn causes the control relay EXR to be released to start the warning period of the highway crossing signal S. Signal S is thus operated while this train advances through sections 2T and 1T and a warning period of substantially 20 seconds is provided.

Assuming a train traveling just under 30 miles per hour approaches, this train consumes a little over 20 seconds in advancing through the measuring section 4T and the time element relay 1ETR is operated to its extreme position to close contact 27 so that it is retained energized while the train is in section 3T. The relay 1ETR in turn closes the second path of the line circuit, and relay EXR is retained energized. The second time element relay 2ETR is operated to close its contact 30 while this train advances through the section 3T since the train will consume a little over 20 seconds in traveling the section 3T. Relay 2ETR then is retained at its extreme position when the train is in section 2T with the result the control relay EXR is held energized while the train is in section 2T. When this train enters section 1T to shunt track relay 1TR, relay 2ETR and the control relay EXR are deenergized, the release of the control relay causing the warning operation of the highway crossing signal. This train moving at little less than 30 miles per hour will consume slightly over 20 seconds in advancing through section 1T to the intersection, and hence the warning period of the signal is substantially 20 seconds.

Operation of the apparatus for a train traveling at any speed other than that explained hereinbefore will be apparent by an inspection of the drawing taken in connection with the de-

scription of the operation of the apparatus for train speeds of 90, 60 and 30 miles per hour.

Although I have herein shown and described but one form of apparatus for the control of highway crossing signals embodying my invention, it is understood that various changes and modifications may be made therein within the scope of the appended claims without departing from the spirit and scope of my invention.

Having thus described my invention, what I claim is:

1. In combination, a stretch of railway track intersected by a highway at which a highway crossing signal is located; a first, a second and a third track section formed in the order named to one side of the intersection, each said section having a normally energized track relay; a time element relay including a clutch winding, an operating winding and a contact actuating member; said time element relay operable to move said member from an initial to an extreme position in a predetermined time interval when said clutch winding is energized and said operating winding is supplied with time spaced current impulses, means including a coder to supply such current impulses to said operating winding, means including a back contact of the track relay of said third section and a front contact of the track relay of said second section to energize said clutch winding, other means including a contact of said time element relay closed at said extreme position and a front contact of the track relay of said first section to energize said clutch winding, and a control circuit having two alternative paths for governing said signal, a first one of said paths including a front contact of the track relay of each of said first and second track sections and the second of which paths includes a front contact of the track relay of said first section and a contact of said time element relay closed only at said extreme position.

2. In combination, a stretch of railway track intersected by a highway at which a highway crossing signal is located; a first, a second, a third and a fourth section formed in the order named to one side of said intersection; each of said sections having a normally energized track relay; a first and a second time element relay each including a clutch winding, an operating winding and a contact actuating armature; each of said time element relays operable to move its armature from an initial to an extreme position in a time interval individually predetermined for each relay when its clutch winding is energized and its operating winding is supplied with time spaced current impulses of a preselected frequency, means including a coder to supply such current impulses to said operating windings, means to energize the clutch winding of said first time

element relay and including a first path through a back contact of the track relay of said fourth section and a front contact of the track relay of the third section and a second path through a front contact of the track relay of the second section and a contact of the first time element relay closed only at its extreme position, means to energize the clutch winding of said second time element relay and including a first path through a back contact of the track relay of said third section and a front contact of the track relay of the second section and a second path through a front contact of the track relay of the first section and a contact of the second time element relay closed only at its extreme position, and a control circuit for said signal including a front contact of the track relay of each of said first, second and third sections and having a first alternative path through a contact of said first time element relay closed at its extreme position to shunt the front contact of the track relay of the third section and a second alternative path through a contact of said second time element relay closed at its extreme position to shunt the front contact of the track relay of said second section.

3. In combination, a stretch of railway track intersected by a highway at which a highway crossing signal is located; a first, a second and a third traffic controlled device spaced in the order named to one side of the intersection; each said device operable from a first to a second position when a train moves past the device; a time element relay including a clutch winding, an operating winding and a contact actuating member; said relay operable to move said member from an initial to an extreme position in a pre-selected time interval when said clutch winding is energized and said operating winding is supplied with time spaced current impulses, means including a coder connected to said operating winding to supply such current impulses, a first circuit including in series a second position contact of said third device and a first position contact of said second device to energize said clutch winding, a second circuit including in series a contact of said relay closed at said extreme position and a first position contact of said first device to energize said clutch winding, and a control circuit having two alternative paths for governing said signal, a first one of said paths including in series a first position contact of each of said first and second devices and a second one of which paths includes in series a first position contact of said first device and a contact of said time element relay closed only at said extreme position.

CARL F. LOWER.
